CLAIM

The ornamental design for a tool handle hammer end and hang hole, as shown and described.

DESCRIPTION

FIG. 1 is a lower, proximal end, right side, perspective view of a tool handle hammer end and hang hole, showing my new design; the broken lines indicating a handle and blade are shown for illustrative purposes only and form no part of the claimed design;

FIG. 2 is an upper, distal end, right side, perspective view thereof;

FIG. 3 is a right-side elevational view thereof, the left side being a mirror image thereof;

FIG. 4 is a proximal end elevational view thereof; and,

FIG. 5 is a top plan view thereof; the bottom plan view being a mirror image thereof.

1 Claim, 3 Drawing Sheets
